DESIGN FOR A SHAKER PACKAGE

Roderick W. Hoag, Melrose, Mass.

Application January 26, 1948, Serial No. 144,020

Term of patent 14 years

(Cl. D59—2)

To all whom it may concern:

Be it known that I, Roderick W. Hoag, a citizen of the United States, residing at Melrose, in the county of Middlesex and Commonwealth of Massachusetts, have invented a new, original, and ornamental Design for a Shaker Package, of which the following is a specification, reference being had to the accompanying drawing, forming part thereof.

In the drawing:

I claim:

The ornamental design for a shaker package, as shown.

RODERICK WM. HOAG.
